Inventor

United States Patent Office.

JOSEPH F. KELLEY, OF WASHINGTON, DISTRICT OF COLUMBIA.

Letters Patent No. 99,909, dated February 15, 1870.

IMPROVEMENT IN WATER-METERS.

The Schedule referred to in these Letters Patent and making part of the same.

To all whom it may concern:

Be it known that I, JOSEPH F. KELLEY, of Washington city, in the District of Columbia, have invented certain new and useful Improvements in Water-Meters; and I do hereby declare that the following is a full, clear, and exact description thereof, reference being had to the accompanying drawings which make part of this specification, and in which—

Figure 1 represents an elevation of a water-meter, embracing my improvements.

Figure 2 represents a partial sectional view of the tubing of the meter, showing the driving-screw of the registering mechanism.

Figure 3 is an elevation of the screw detached from the water-tube, constructed with vanes or ribs.

Figure 4 represents the ratchet and spring, for preventing any retrograde movement of the registering mechanism.

Figure 5 represents a face view of the dial and index-hands.

In the accompanying drawings the tubing of the meter consists of three sections: a T-shaped egress section, A, upon which the registering mechanism is mounted and supported; a curved ingress section, C; and an intermediate straight coupling section, B, having cut upon its extremities screw-threads, for the purpose of connecting the end sections A C.

Within the intermediate tube B a screw, E, is arranged, the axial shaft of which is supported in bearings in a cross-bar, h, at the rear end of said tube, and at m, in the front side of the T-shaped section A.

The end of the axial shaft projects through and beyond the T-shaped section to receive a pinion, k, which engages with suitable registering mechanism.

The supporting cross-bar h serves also as a break, to interrupt the continuity of the water at the entrance of the tube B, and cause it to be projected against the screw at an angle, instead of in a direct line.

The revolving screw is made to fit accurately in the intermediate section B, so as to revolve freely therein, while its worm perfectly fills the tube, so that the water cannot escape through it except over the driving surfaces of the screw.

The screw is provided on its driving or inner surface with smaller flanges or buckets, a, placed on the acting or driving surface of the screw at proper intervals

throughout its length, for the purpose of acting as stops to the gliding passage of the water, to agitate or ruffle it, thereby rendering absolutely certain the action of the screw, whatever may be the force of the flow of water against it, as it frequently happens that the water passes over and through the screw without turning it sufficiently to register the full amount of water which has passed through. These flanges or buckets have only sufficient projection from the surface of the screw to produce the result above stated, and cannot, therefore, materially retard the passage of the water, while a perfect action of the screw is obtained.

The upper end of the T-shaped egress section A is fitted with a screw-tap, b, which may be removed, when necessary, to afford facility for cleaning out the tube.

The registering mechanism is supported upon and secured directly to this section of tube A by means of a screw, d, passed through the head of the screw-tap b into the frame of said mechanism, and a bracket, c, bolted to the lower end of said section and to the bottom of the said frame.

By means of this attachment the meter is rendered very compact, and the whole mechanism can be fitted and supported within a box a very little larger than the diameter of the dial-plate; and it can be readily removed from the tubing for repairs, or to be replaced by any other suitable mechanism.

The axial shaft of the screw is provided with a ratchet-wheel, into the teeth of which a spring ratchet-pawl fits, to prevent any retrograde movement of the registering mechanism, as shown in figs. 1 and 4.

Having described my invention,

I claim—

The combination and arrangement of the water-tube B, the removable T-shaped section A, and the removable screw-tap b, by which the attachment and support of the registering mechanism is rendered compact, its removal and replacement effected with facility, and admitting of the cleaning out of the tube when clogged, in the manner herein shown and described.

JOS. F. KELLEY.
